WALL FIXTURE

Misha Schreibman, Washington, D. C.

Application November 4, 1948, Serial No. 58,177

3 Claims. (Cl. 248—30)

1
This invention relates to an ornamental wall fixture. Most particularly, it relates to a combination plate holder and lighting fixture.

It is an object of the invention to provide a device having useful and ornamental features wherein decorative plates such as dinner plates and the like can be mounted for hanging on the wall, and to combine this with a lighting fixture.

Broadly the invention comprises a base, means for mounting the base on a wall, a plurality of adjustable members operatively associated with the base to firmly grip a plate and hold it in position, and a plurality of light fixtures attached to the base and extending forwardly thereof adjacent its lower portion.

Figure 1 is a front view of the device with the outline of a plate in operative position. Figure 2 is a section through at lines 2—2. Figure 3 illustrates a modification of the base. Figure 4 is a partial section of the latter device through lines 4—4.

The invention will be understood by reference to the drawings and the following description thereof. Various modifications within the scope of the invention will be apparent to one skilled in the art. A base member 1 may comprise a circular ring or hoop made of metal or other suitable material. A flat strip is welded or otherwise secured to form a continuous cylinder. Fastened to the back of the circle, and flush therewith, is a metal strip 2 which contains means for hanging or otherwise mounting the device on a wall. This may comprise a keyhole shaped slot or opening 3 for mounting the base on the wall, for example, by means of a nail 4. Other hanging means will be apparent to one skilled in the art.

Spaced at intervals about the cylindrical ring 1 are a series of slots for receiving the adjustable plate holding members 5. These may comprise flat metal strips slotted at 6, having hooks 7 at the outer end. The hooks are bent in such a manner as to fit over the edge of the dinner plate 8 which is shown in skeleton form by dotted lines. The strips 6 intersect at the center of base 1 and are retained by bolt 10 extending through the slots and through crosspiece 9 which is drilled or punched to receive the bolt. The crosspiece is attached by soldering, welding or otherwise, to either side of the ring about midway between the back and front edges, so that the head of bolt 10 clears the wall when the assembled piece is hung. By loosening the nut on bolt 10 and moving the members 5 inwardly or outwardly the

device can be made to accommodate and firmly hold plates of differing diameters.

The diameter of ring 1 is sufficient so that the conventional base of a plate will fit inside the ring which aids in holding it firmly in position after the hooks have been secured.

2
A plurality of light holding members 11 are fixed to the circular member 1 by any conventional means. They may be brazed, soldered or welded in position or may be held in position by suitable screw connections with or without retaining bolts and lock washers. The members 11 are preferably tubular, especially when the device is wired for electric lights. The fixture is illustrated as a candle holder in Figure 1, but can be made for electric lights by attaching a suitable bulb socket in place of the candle socket 12 and by passing an electric wire through the tubular members. Although shown with three candle holders, one, two or more can be used. In this case, an opening is provided for introducing the electric lead wire which may be of sufficient length to lead to a suitable floor or wall receptacle. It is obvious that a wall receptacle could be supplied at the point where the fixture is hung so that a plug connection could be made and concealed by the plate 8. Otherwise the lead wire could be dropped through an opening in ring 1 to a floor plug in the conventional manner associated with the so-called pin up type of light fixture. This could be done by omitting the central tubular member and using the hole in the base for the lead in wire. The light holders preferably extend upward to about the bottom of the plate 8 when it is in position, although this is a matter of choice.

Other means could be used for mounting the fixture on the wall than that illustrated but this is a preferred design because of the simplicity involved and because the strip 2 tends to stiffen the base.

A modification of the device is illustrated in Figures 3 and 4 without, however, showing the light fixtures which may be substantially the same as those shown in Figures 1 and 2. In this case the base plate 1 may be pressed or punched from a single sheet of metal providing a sloping outer wall 12, a rim 13, and a recessed section 14 within which the base of the decorative plate is accommodated. The depressed portion is sufficiently deep to accommodate the plate, but not so deep that bolt 10 strikes the wall when the device is hanging. The plate members 5 are similar to those illustrated in Figures 1 and 2 and are adjustable in a similar manner. A similar

3

wall mounting device 2 may be provided. The sloping walls 12 and 14 are slotted to retain members 5 which intersect at the center and are secured by bolt 10 extending through a central hole in the metal floor of the recess. Their operation is similar to that of the modification shown in Figure 1.

In operation, the central nut is loosened and the retaining members 5 are slid out until hooks 7 permit the plate to be put in position with the base ring inside of cylinder 1. The hooks are brought firmly against and over the edges of the plate and adjusted until the plate is centered. The nut of bolt 10 is tightened. The plate is now in position and firmly held. The device may then be hung on a wall, post or elsewhere. The ornamental plate hides the mechanisms except for the light holders 11 which extend downwardly, outwardly and then upwardly.

The fixture is not only novel in that it permits a plate to be mounted on the wall which is often done for obtaining interior decorative effects, but it likewise serves the purpose of a pin up type of wall lighting fixture. It offers the additional advantage that plates of various sizes and ornamented in various ways can be used. The user of the device is not only provided with light but can by a simple operation, change the character and appearance of the lighting fixture simply by choosing a plate having a different design or color scheme. It is especially adapted to the hanging of ornamental antique plates popularly used as wall ornaments in homes. The user is not limited to the available designs of the usual pin up lamp, but has the choice of the variety of different dinner and serving plates available.

The plate is illuminated, which adds to the decorative effect. The plate may also serve as a reflector, thus increasing the benefits to be obtained.

The fixture is simple and inexpensive to construct. It is easily mounted, and the plates can be changed by any one with a minimum of effort or skill.

In addition to domestic use, it furnishes an excellent method for displaying plates in gift shops and the like.

When the light holders form a candelabra, the device is particularly fitting to the style and decorative effects of mounted plates.

The invention is not to be construed to be limited to the exact forms shown, which can be varied by one skilled in the art without departing from the spirit thereof.

I claim as my invention:

1. An ornamental lighting fixture and plate holder comprising a base member, said base mem-

ber comprising a cylindrical ring of sheet metal, means for mounting said fixture on a wall, a central cross-member disposed intermediate the width of said ring, spaced slots adjacent the forward edge of said ring, plate retaining members passing slidably through said slots at an angle to intersect at the center of said ring, adjustable means for rigidly fixing the position of said plate retaining members to said cross-member at the center of said ring, and a light holder attached to the ring, said light holder extending downwardly, outwardly and upwardly from the ring.

10 2. An ornamental combination plate holder and lighting fixture comprising a substantially circular base, means for mounting the base on the wall, a plurality of slots spaced circumferentially in said base, a plurality of adjustable plate retaining members extending through said slots and intersecting at the center of the circular

20 base, said plate retaining members comprising hooked strips slotted adjacent the end opposite the hook, means at the center of said base for adjusting the plate retaining members to accommodate plates of different diameter and for 25 fixing the plate retaining members in a predetermined position, and a plurality of light holders attached to the base, said light holders comprising tubular elements extending downwardly, outwardly and upwardly from said base.

30 3. An ornamental plate holder comprising a substantially circular base, means for mounting said base on a wall, a plurality of slots spaced circumferentially in said base, a plurality of adjustable plate retaining members extending through said slots and intersecting at the center of the circular base, said plate retaining members comprising strips having hooks at their outer ends and slots adjacent their inner ends, means at the center of said base for adjusting said 40 plate retaining members to accommodate plates of different diameters and for fixing the plate retaining members in adjusted positions, and an elongated article supporting member secured to said base and extending downwardly, outwardly 45 and upwardly therefrom to support on its free end an article in juxtaposition to the face of a plate mounted on said holder.
